UNITED STATES PATENT OFFICE.

FLOYD J. METZGER, OF NEW YORK, N. Y., ASSIGNOR TO AIR REDUCTION COMPANY,
INCORPORATED, A CORPORATION OF NEW YORK.

TRANSPORTATION OF HYDROCYANIC ACID.

1,408,757.

Specification of Letters Patent. Patented Mar. 7, 1922.

Application filed January 27, 1920. Serial No. 354,419.

To all whom it may concern:

Be it known that I, FLOYD J. METZGER, a citizen of the United States, residing at New York, in the county of New York, State of New York, have invented certain new and useful Improvements in the Transportation of Hydrocyanic Acid; and I do hereby declare the following to be a full, clear, and exact description of the invention, such as will enable others skilled in the art to which it appertains to make and use the same.

This invention relates to fumigation and particularly to the transportation and use of hydrocyanic acid for this purpose.

An object of the invention is the provision of a vessel for hydrocyanic acid in which it may be safely transported, which will absorb and neutralize hydrocyanic acid accidentally released, and from which the hydrocyanic acid may be readily withdrawn for use.

Further objects and advantages of this invention will be apparent as it is better understood by reference to the following specification when read in connection with the accompanying drawing illustrating the preferred embodiment of my invention, in which—

Fig. 1 is a longitudinal section through a container for hydrocyanic acid; and

Fig. 2 is a section on the line 2—2 of Fig. 1.

Hydrocyanic acid has been used heretofore as a fumigating material to destroy germ, insect and animal life. Use of this material has, however, been restricted because of the necessity of generating the hydrocyanic acid in situ, by the treatment of an alkali metal cyanide with sulphuric acid. This method is unsatisfactory, involving as it does the handling of reagents such as sulphuric acid and the carrying out of a chemical reaction under unfavorable conditions.

Under such conditions, the available hydrocyanic acid is not efficiently released and a sludge containing decomposition products, sulphuric acid and more or less polymerized hydrocyanic acid remains. This sludge is inherently dangerous and is disposed of with difficulty. Furthermore, the floors, walls and furniture of the room or enclosure in which the reaction is carried out are frequently damaged by the sulphuric acid; and workmen are sometimes injured

because of their unfamiliarity with chemical reactions.

I have discovered that liquid hydrocyanic acid, or water solutions thereof, may be advantageously used as a fumigating agent, the liquid being disposed in a suitable receptacle within the enclosure or room to be fumigated and evaporated from the receptacle. The advantages of such procedure are numerous. All of the hydrocyanic acid is available for fumigating purposes and no sludge or residue remains for subsequent disposal. It is no longer necessary to transport reagents to be mixed at the place to be fumigated, sulphuric acid is eliminated and the only manipulation required is the placing of the hydrocyanic acid or solution thereof in suitable receptacles from which it is to be evaporated.

The hydrocyanic acid is advantageously transported in containers holding a unit charge sufficient to fumigate a room, having a capacity, for example, of one thousand cubic feet. The size of the unit charge is of course arbitrary and may be varied. The hydrocyanic acid in such a charge may be in liquefied form or it may be in a water solution thereof. In practice I have found that a 75% solution of hydrocyanic acid is very desirable since it does not develop material pressure in a closed container at normal atmospheric temperature, but, nevertheless, readily vaporizes when exposed to the atmosphere. Thus when such a solution is poured into an open receptacle and exposed in a room or enclosure the entire charge will evaporate within a short time, which may be lessened by employing a wick to increase the evaporating surface.

Hydrocyanic acid is a dangerous material unless its use is carefully safeguarded. The fact that it evaporates spontaneously when exposed to the atmosphere makes it necessary to observe due precaution to prevent accidental escape of the acid from the container in which it is transported. Glass or ceramic containers are preferably employed because metals are slowly attacked by the acid. It is desirable, therefore, to provide means to absorb and neutralize any hydrocyanic acid which may escape from the container and particularly in the event of breakage of the container it is essential that all of the hydrocyanic acid be held and

prevented from vaporizing into the atmosphere.

I have discovered that the desired result may be readily and safely accomplished through the provision of absorbent and neutralizing means surrounding the container and disposed within a suitable casing therefor. For this purpose I prefer to employ a mixture of absorbent carbon or charcoal and slaked lime (calcium hydroxide) in which a quantity of water is preferably absorbed to render the material more active. Other absorbent material may be used. For example, caustic soda (sodium hydroxide) may be substituted for the slaked lime in the mixture; slaked lime without carbon may be employed; and sawdust or kieselguhr, may be substituted for the carbon.

When hydrocyanic acid is released in contact with slaked lime or mixtures such as are above described, a part of the hydrocyanic acid is absorbed; a part is chemically neutralized; a part may be hydrolyzed, and another part may be polymerized. No exact explanation of the mode by which the hydrocyanic acid becomes ineffective is possible or necessary, and any or all of these functions may be carried out in the mass simultaneously or successively. It is a fact, however, that a sufficient supply of the slaked lime or mixture will prevent the escape of hydrocyanic acid to the atmosphere.

Referring to the drawing in which I have illustrated by way of example, one form of a transportation vessel adapted to accomplish the desired result, 5 indicates a glass or other suitable container, an 8 oz. bottle being sufficiently large to contain the unit charge above described. The container is preferably provided with a stopper 6 and rubber gasket 7, the stopper being held in place by the common form of locking device 8, frequently employed in soda water bottles. The container 5 is disposed within an outer casing 9 which may be made of paper, metal or other suitable material and is preferably closed by a screw cap 10. A cage 11 which may be constructed of wire, for example, may be provided to hold the container 5 centrally within the casing 9, the legs 12 of the cage bearing against the wall of the casing.

The space within the casing 9 and about the container 5 is filled with absorbent material 13 and in the preferred embodiment of my invention I employ four (4) parts by weight of absorbent carbon or charcoal, four (4) parts by weight of slaked lime (calcium hydroxide) and three (3) parts by weight of water, the whole being thoroughly mixed prior to disposal within the casing 9. The amount of water used is not sufficient to moisten the material perceptibly, but serves to hasten absorption of the hydrocyanic acid. It is to be understood that the

proportions may be varied and that active materials may be substituted for those mentioned to accomplish the primary purpose of the invention.

In the practical application of my invention, I have found that the entire charge of hydrocyanic acid sufficient to fumigate a room of one thousand cubic feet capacity may be released in the surrounding material as hereinbefore described and that no effective amount of hydrocyanic acid will escape. The breakage of a container, therefore, even in a confined space is immaterial and the otherwise dangerous acid is rendered harmless.

From the foregoing it will be readily understood that I have perfected means which makes the use of hydrocyanic acid as a fumigating agent practically possible. In the container protected as above described the acid may be safely transported by and in common carriers without danger to employees or the public generally. To use the acid it is necessary merely to remove the screw cap 10, withdraw the container, open the same and pour the acid into a suitable receptacle, preferably a shallow tray, which may be provided with a wick to increase the evaporating surface.

Various changes may be made in the form and arrangement of the vessel and in the material employed without departing from the invention or sacrificing any of its advantages.

I claim:

1. A transportation vessel for hydrocyanic acid, including a container for the acid, and a neutralizing composition comprising an absorbent and a material capable of reacting chemically with said acid, said composition being disposed about said container.

2. A transportation vessel for hydrocyanic acid, including a container for the acid, and a neutralizing composition, comprising absorbent carbon and a material capable of reacting chemically with said acid, said composition being disposed about said container.

3. A transportation vessel for hydrocyanic acid, including a container for the acid, and a neutralizing composition comprising an absorbent and calcium hydroxide, said composition being disposed about said container.

4. A transportation vessel for hydrocyanic acid, including a container for the acid, and a neutralizing composition comprising absorbent carbon and calcium hydroxide, said composition being disposed about said container.

5. A transportation vessel for hydrocyanic acid, including a container for the acid, and a neutralizing composition comprising absorbent carbon and calcium hy-

- droxide, said composition containing in addition a proportion of moisture and being disposed about said container.
6. A transportation vessel for hydrocyanic acid, including a container for the acid, and a neutralizing composition containing an absorbent, a material capable of combining chemically with said acid and a proportion of moisture, said composition being disposed about said container.
7. A neutralizing composition for hydrocyanic acid, comprising an absorbent and a material capable of combining chemically with said acid.
- 15 8. A neutralizing composition for hydrocyanic acid, comprising an absorbent material and calcium hydroxide.
9. A neutralizing composition for hydro-
- cyanic acid, comprising absorbent carbon and a material capable of combining chemically with said acid. 20
10. A neutralizing composition for hydrocyanic acid, comprising absorbent carbon and calcium hydroxide finely divided and intimately commingled. 25
11. A neutralizing composition for hydrocyanic acid, comprising absorbent carbon, calcium hydroxide and a proportion of water, said material being in a substantially dry pulverized condition. 30
12. A composition for rendering hydrocyanic acid non-toxic, comprising an absorbent and a material capable of causing decomposition of said acid.

In testimony whereof I affix my signature. 35

FLOYD J. METZGER.
